(57)

CLAIM

The ornamental design for an awning, as shown and described.

DESCRIPTION

FIG. 1 is a front view of an awning, showing my new design; FIG. 2 is a rear view thereof;

FIG. 3 is a top view thereof;

FIG. 4 is a bottom view thereof;

FIG. 5 is a lateral view (right side) thereof;

FIG. 6 is a lateral view (left side) thereof; and,

FIG. 7 is a perspective view thereof (seen from obliquely front/above). The broken lines shown in the drawings are for environment purposes only and form no part of the claimed design.
